SOUND RECORDING APPARATUS

Herbert S. Berliner, Westmount, Quebec, Canada

Application April 20, 1943, Serial No. 483,712

7 Claims. (Cl. 274—13)

This invention relates exclusively to the incorporation of change feed means in that type of phonograph disc recording machine wherein the feed screw for the recording head is driven in a positive manner from the top of the recording machine turntable.

An object of the invention is to provide in a phonograph disc recording machine including a turntable, a carrier arm swivelly mounted for positioning over said turntable, a recording head on said carrier arm, a feed screw mounted by said carrier arm for feeding said recording head across a record blank disc on said turntable, and means for driving said feed screw from the upper side of said turntable, a mechanism for changing the regular speed at which said screw is driven from the top side of the turntable and hence the regular rate at which the recording head is caused to travel across the turntable.

Another object is to provide a means for the purpose stated and which is of simple and inexpensive construction, easy and convenient to operate and which is positive in its results.

Other objects and advantages will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a plan view of a recording machine having the change feed means of the invention incorporated therein;

Fig. 2 is a front elevational view of said machine;

Fig. 3 is a transverse vertical sectional view taken substantially along the plane of the line 3—3 of Fig. 1, with a portion of the housing broken away to show a worm and worm gear drive;

Fig. 4 is a perspective view showing the general relation of the parts of my variable speed drive;

Fig. 5 is a vertical sectional view taken substantially along the plane of the line 5—5 of Fig. 3;

Fig. 6 is a detail sectional view taken substantially along the plane of the line 6—6 of Fig. 5, and showing a ratchet mechanism forming part of an overrunning clutch device with which the recording machine is equipped; and

Fig. 7 is a vertical sectional view taken sub-

stantially on the plane of the line 7—7 of Fig. 5, and showing a detail of the operating lever for the feed change device.

There are many reasons why it is desirable to have a sound recording machine include means for changing the regular rate of feed of the recording head across a disc record blank. An important, if not the principal, reason is to have the same machine capable of recording both commercial phonograph records and phonograph records especially made for electrical transcription purposes. Ordinary commercial phonograph records are recorded at approximately 78 revolutions per minute and with 90 to 100 grooves per inch leaving a substantial wall between adjacent grooves while records for electrical transcription purposes are usually recorded at 33½ revolutions per minute and are made with their sound grooves closer together.

Referring in detail to the accompanying drawings, the recording apparatus as here shown includes a turntable 12 driven by any mechanism (not shown) usual in the art and contained and mounted on a suitable base 11. A recording head 14 equipped with a recording stylus 15 is supported by a carriage 16 which during operation of the apparatus is impelled across the turntable by a feed screw 17. Feed screw 17 is rotatably mounted in a carrier arm generally designated 18 and including end brackets 19 and 20 rigidly connected in spaced relation by elongated bearing means comprising tie rods 21. In the particular embodiment shown there are two such bearing means having their axes parallel and spaced apart in substantially vertical relation as shown clearly in Fig. 3.

From a recording position over the turntable 12 the entire carrier arm 18 and the parts mounted thereon may be swung vertically and laterally to clear the turntable for the placing of a new record blank thereon, and the like. To this end a base bearing member 22 is secured to the base 11 at one side of the turntable and receives a vertical standard or post 23 connected at its upper end with a horizontal shaft 24 to which is pivoted a housing means 25 comprising part of the carrier arm 18. With this arrangement it will be clear that the carrier arm may be swung vertically about the horizontal shaft 24 and that then the entire assembly may be swung laterally, the post 23 turning in the base bearing 22, whereby to dispose the carrier arm and recording head and associated parts to one side or beyond one edge of the turntable.

55 A stub shaft 26 passes through the end bracket

19 and is rotatably received in a hollow housing member 27 secured to such bracket as by screws 28 and comprising a handle means by which the entire assembly of the carrier arm may be lifted and swung to and from a recording position. Shaft 26 is secured against casual longitudinal movement by a set screw 29 passing radially through a wall of the housing 27 and entering an annular groove 30 in the shaft.

The extreme inner end of shaft 26 is cone shaped as at 31 to function as a trunnion or bearing for one end of the feed screw 17 as best shown in Fig. 5. At its other end the feed screw is supported on the cone shaped inner end 32 of a shaft 33 mounted in a bearing sleeve 34 slidably disposed in a housing 35 located at the outer side of end bracket 20. The shaft 33 is freely turnable in sleeve 34 and the sleeve and shaft are both slidable in the housing 35 and through the end bracket 20 whereby the cone bearing 32 may be moved to and from supporting relation with an end of the feed screw 17 to permit of the latter being removed and replaced. A thumb screw 35a or the like passes through end bracket 20 and may be tightened against the sleeve 34 for the purpose of securing the latter and the shaft 33 in position.

Feed screw 17 is driven from the top of the turntable 12. For this purpose the carrier arm 18 at its inner end is provided with a driving flange 36 having a center hole and having holes 37 radially spaced from said center hole. The center hole (not shown) receives the usual centering pin of the turntable and when the carrier arm is in recording position the holes 37 receive driving studs 38 provided on the turntable whereby as the turntable is rotated it drives the flange 36. It will be understood that any record blank 39 on the turntable has the usual center opening and openings radially spaced from said center opening to receive one or more of the turntable carried studs or pins 38.

As shown in detail in Figs. 2 and 3 the flange 36 is secured to or made integral with the lower end of a vertical shaft 40 which carries a worm 41 constantly meshing with a worm gear 42 turnable about the stub shaft 26. According to the present invention the worm gear 42 drives the feed screw 17 through a change speed mechanism later to be described in detail.

To the desired end, worm gear 42 has rigidly secured thereto a housing 43 receiving a pawl and ratchet mechanism as clearly shown in Fig. 6. Such mechanism includes a pawl 44 normally forced inwardly toward the axis of the housing under the urging of a coil spring 45 set in a recess in the housing and at one end bearing against the pawl. The pawl engages a ratchet wheel 46 within the housing and fixedly secured to the stub shaft 26 on which the worm gear is turnable. With the described construction it will be clear that as the worm gear 42 is rotated by the worm 41 it acts through the housing 43, pawl 44 and ratchet wheel 46 to rotate the stub shaft 26 at a fixed speed relative to the rate of rotation of the turntable 12.

A gear 47 is fixed to the inner end portion of the stub shaft 26 as by means of a set screw or the like 48. An idler gear 49 meshes with gear 47 and is supported by a stud 50 projecting from the inner face of a plate 51 which may comprise an integral extension of end bracket 18 or may be fixed thereto as desired. A shaft 52 is fixedly carried by plate 51 and projects at each side thereof and at the inner side thereof rotatably

mounts a gear 53 constantly meshing with the idler gear 49. The purpose of the idler gear 49 is to cause gear 53 to rotate in the same direction as gear 47.

5 Gear 53 may be attached to or formed integral with a relatively long gear 54 shown as of somewhat less diameter than the gear 53. Gears 53 and 54 are held in place on the shaft 52 in any suitable manner, as, for example, by a screw 55 entering the inner end of the shaft. Gears 53 and 54 being integral or attached to one another are turnable as a unit on the shaft 52.

Slidable and turnable on the fixed shaft 52 at the outer side of the plate 51 is a collar 56 provided with a thumb screw 57 by means of which the collar may be secured in the desired fixed position on said shaft. Attached to the inner end of the collar 56 is a radially extending arm 58 to which is fixed one end portion of a rod 59 disposed in parallel relation to the shaft 52 and passing through an arcuate slot 60 provided in the plate 51. Clearly on loosening of screw 57 the collar may be moved along and about the shaft 52 and corresponding movements will be imparted to the rod 59 but in spaced parallel relation to the shaft 52.

Attached to the inner end of rod 59 is a bracket arm 61, shown as arcuate, and the lower end of which supports a shiftable idler gear 62. With 30 the described arrangement on loosening of screw 57 the idler gear 62 may be shifted back and forth in the direction of the length of gear 54 and may also be given a planetary movement partly about such gear. These movements are imparted to gear 62 by manual shifting of the collar 56 on the outer end portion of the fixed shaft 52 it being understood that said collar constitutes the supporting means for the arm 58, rod 59, bracket 61 and the idler gear and supports such elements 40 from the outer end portion of the fixed shaft 52.

A stepped gear 63 is fixed on the inner end portion of the feed screw 17 adjacent the inner end of the stub shaft 26. As shown gear 63 has varying diameters or steps 1, 2, 3, 4 and 5 although 45 it will be understood that such gear may have greater or lesser number of steps as may be desired. The manner in which the gear is attached to the feed screw is not of prime importance and here a set screw 64 is shown as passing through the gear and into a milled slot 65 in the unthreaded end portion of the feed screw.

The gear 63 is so positioned on the feed screw 17 that when the latter is secured in place or 55 mounted on the cone-shaped ends of the shafts 26 and 33 the steps of said gear are adapted to be selectively engaged by the shiftable idler gear 62 while the latter is meshing with the relatively long gear 54. Thus from Figs. 4 and 5 it will be clear that upon loosening of thumb screw 57 and 60 manual adjustment of collar 56 along and about the outer end portion of shaft 52 the idler gear 62 while remaining in mesh with gear 54 may be brought into meshing relation with any of the steps of gear 63.

For example, when the idler is meshing with gear 54 and step 1 of gear 63 the idler is disposed somewhat toward one side of the gear 54. As the idler is shifted to successively connect gear 54 in driving relation with the steps 2, 3, 4 or 5 of gear 63 the idler is moved not only along the gear 54 but also downwardly about the same, the axis about which the idler is moved being the shaft 52 which is also the axis of gear 54. Thus 75 when gearing 54 with step 5 of gear 63 the idler

is substantially under gear 54 as suggested by the dotted lines in Fig. 4.

After idler gear has been adjusted to a desired position with a desired step of gear 63 geared to gear 54 the thumb screw 56 is again tightened to secure the parts against casual relative movement. It will be clear that depending on which step of gear 63 is geared with the gear 54 the feed screw 17 will be driven at a greater or lesser rate relative to the rate of rotation of the turn-table. Thus with the structure described it will be clear that the ratio between the rate of rotation of the turn-table and that of the feed screw 17 may be almost instantaneously changed by the operator. The change is made without disassembling or removing any parts or otherwise disrupting the mechanism and without loss of time.

The change speed gearing described is preferably enclosed in a suitable housing or gear box 66 and indicating means is provided in order to give an external indication of the position of the idler gear 62 within said gear box. For the mentioned purpose a finger piece 67 is secured to the arm 58 and extends upwardly therefrom as shown. A stepped bracket 68 is secured to the plate 51 and provided with a series of slots 69 into which the finger piece 67 enters as the idler gear 62 is moved from one engagement with one of the steps (1, 2, 3, 4 or 5) into engagement with another thereof. Bracket 68 may be provided with suitable indicia (not shown) associated with each of the steps 69 thereof. For example, such indicia might be in terms of the number of lines or grooves per inch of record surface to be made by the recording stylus with the finger piece 67 in each step of the bracket or the indicia might be such as to give any other useful information in connection with the location of the finger piece in any one of the steps of the bracket. In addition, the various steps of the bracket 68 cooperate with finger 67 to limit movement of gear 62 as it is moved into mesh with the respective steps of gear 63.

The machine disclosed includes means for manually operating the feed screw 17 at a higher rate of speed than is possible with the regular means above disclosed whereby a high pitch cross over groove may be cut in a record blank as between a pair of selections or from the end of the recording to a terminal circle or the like. To this end, shaft 33 is provided with a pin 70 entering a slot 71 milled in the outer end portion of the feed screw 17 as shown in Figs. 1 and 2.

In this way a driving connection is established between the shaft 33 and the feed screw. A crank disc 72 is rigidly attached to or is formed integral with the outer end of the shaft 33 and is provided with a handle 73 by means of which the shaft 33 and accordingly the screw 17 may be manually rotated. By virtue of the overrunning clutch mechanism previously described it will be seen that by manual operation of the crank 73 the feed screw 17 can be rotated at a speed greater than that normally imparted to it by the turn-table drive mechanism so that the recording head carrier can be moved across the surface of the turn-table at a correspondingly greater-than-normal speed to provide a high pitch cross over groove from one recorded zone to the start of another or from a recorded zone to a terminal circle or the like.

Recording head carriage 16 is for convenience and by way of illustration supported upon the upper of the two elongated bearings 21 to which reference has already been made. The carriage

is adapted for relatively limited rotary movement about the axis of the upper bearing 21, it being supported in operating position against the lower bearing 21 in the usual manner. Carriage 16 is provided with a thread-engaging plate 74 (Fig. 2) which, during operation of the device, enters between the threads of feed screw 17, so that by rotation of the latter the carriage 16 carrying the recording head is driven inwardly or outwardly across the turn-table in a direction depending upon whether it is desired to cut the record from the outside toward the center, or from the center toward the outside. In the case of a left-hand threaded feed screw the carriage will travel across the turn-table from the outside of the record blank toward the inside, and conversely in the case of a right-hand threaded feed screw.

Carriage 16 is provided with means to retract plate 74 from operative engagement with the feed screw. Thus, for instance, the plate 74 is connected to thumb-screw 75, through an operating shaft (not shown) extending through the carriage. Thumb-screw 75 and the shaft to which it is attached is caused to rise on rotation of the thumb-screw in one direction. This upward motion continues until plate 74 is withdrawn from contact with the threads of the feed screw 17, thus stopping the travel of the carriage across the turn-table despite the continuous rotation of the feed screw.

For convenience, the apparatus may include a scale which may take the form of a square rod 76, Figs. 2 and 3. This rod is rotatable and contains a number of scales graduated in any desired manner to show the position of the carriage with respect to the record, or it may carry any other desired indicia. A pointer 77 (Fig. 2) having pointed ends 78 may be attached to the carriage 16 for use in connection with the scale 76.

As will be apparent from the foregoing description, the mechanism described comprises means for varying the ratio between the rate of rotation of the turn-table (the driving element) and the rate of rotation of the feed screw (the driven element), thereby permitting the recording stylus 15 to be driven across the record blank in a radial direction at desired predetermined speeds for any given turn-table speed. By this means the spacing between the sound grooves on the record can be varied in a predetermined manner.

More particularly, and merely by way of further illustration, in one specific embodiment of my invention I have constructed apparatus in accordance with my invention in such manner that the gear 63 (Figs. 4 and 5) comprises a series of steps of varying diameters such that when the movable idler gear 62 is caused to mesh with the step of largest diameter (step 1) there will be produced 152 record grooves or lines per inch (measured in a radial direction across the record), the next smallest step will produce 129 lines per inch, the next smallest 118 lines per inch, the next smallest 97 lines per inch, and the smallest of all 86 lines per inch.

These spacings are given only as illustrations. The groove spacings which are generally found to be most desirable for ordinary commercial records are those ranging from about 80 to 110 lines per radial inch, with 96 to 98 most frequently employed. For electrical transcription purposes the records are usually designed to op-

erate at 33½ R. P. M. and have the sound grooves much closer together.

Considering now the operation of the apparatus as a whole, after a blank record disc 39 is placed in recording position upon the turn-table 12, the carrier arm 18 is brought into position with its inner end over the center of the turn-table, and is lowered into operating position with its flange 36 coupled with the turn-table through one or more of the driving studs 38.

Carriage 16 may be released from engagement with feed screw 17 by turning knob 75 (Figs. 1 and 2) in a clockwise direction, thus raising the driving plate 74 from engagement with the threads of the feed screw. The carriage can then be moved along the bearing rods 21 until the recording stylus is over the record at the point where it is desired to begin recording. With a left-hand feed screw 17 as shown in Fig. 2, this point will be near the outer periphery of the disc record blank 39. At the desired point screw 75 may then be turned in the opposite direction, thereby permitting plate 74 to drop downwardly into engagement with the feed screw 17.

The apparatus having been set for the desired gear ratio by placing the movable idler 62 in mesh with the particular step of gear 63 which will produce the desired groove spacing on the record, as shown for example, by appropriate indicia inscribed upon bracket 68 in line with each of the slots provided therein for finger 67, the apparatus is ready to begin recording. The pressure exerted by the recording stylus 15 upon the blank record disc 39 may be controlled as desired by means of spring 79 (Fig. 2), means being also provided for adjusting the tension of this spring, such as an adjusting screw 80.

After the turn-table is rotated a few times the recording may be begun, and continued until the recording of the particular selection or excerpt is completed. Assuming that a series of relatively short sound effects are to be recorded on a single record disc, after each individual sound effect has been recorded, the recording head carriage 16, with or without an additional few revolutions for the turn-table, may be rapidly moved inwardly to a new recording position by manually turning crank 73. This will simultaneously produce a spiral run-out groove between the recorded sound effects on the record. The next sound effect may then be recorded as before, and so on. When in making a recording the plate 74 reaches a recessed groove 81 at the inner end of the feed screw 17, the recording head will remain stationary, despite the continued rotation of the feed screw.

While I have described my invention in connection with the overrunning clutch mechanism shown more particularly in Fig. 6, it is obvious that it is not restricted to use therewith, but may be employed in recording apparatus where there are no particular means provided for producing a spiral run-out groove of increased pitch between recorded portions on the same record disc. Furthermore, while the particular feed screw 17 illustrated in the drawings carries a left-hand thread it is obvious that by providing the lead screw with a right-hand thread the apparatus may be readily converted to one in which the record is cut and played from the inside out.

I am aware that other modifications may be made by those skilled in the art in accordance with the foregoing description. Therefore it is to be understood that changes, omissions, additions, substitutions and/or modifications may be

made within the scope of the following claims without departing from the spirit of my invention.

Having thus set forth the nature of my invention, what I claim is:

5 1. In a recording apparatus comprising a turn-table, a cutting head carrier having a rotatable flange at its inner end for engaging the center of the turn-table, a feed screw mounted by said carrier, a worm gear, an overrunning clutch mechanism associated with the worm gear, a worm driven from the top of the turntable through said flange and meshing with said worm gear, a crank at the outer end of the carrier arm and connected with said feed screw, and a change

10 speed gearing interposed between said overrunning clutch and said feed screw whereby the latter is rotatable from the top of the turn-table at a selected one of a plurality of available predetermined speeds.

20 2. In a disc recording apparatus comprising a turn-table, a recording head, a swiveled removable carrier mounting said recording head and adapted to position the same over a record blank on said turn-table, means for feeding said head on said carrier across a record blank, said means comprising a feed screw in operative engagement with said recording head and gear mechanism for driving said feed screw from the top of said turn-table, means mounting said feed screw and gear mechanism on and for movement with said carrier, said gear mechanism including driving and driven gears of which one is a stepped gear, and a movable gear manually shiftable to gear said driving and driven gears together through a chosen step of said stepped gear.

25 3. In an apparatus for recording sound on a disc, a turntable, a carrier, a recording head on said carrier, a feed screw on said carrier and operable to feed said head across a record blank on said turntable, a gear drive from the top of said turntable to said feed screw and including a worm driven from said turntable, a shaft, a worm gear meshing with said worm and driving said shaft, a spur gear on said shaft, a second shaft spaced from the first shaft and parallel with the feed screw and fixed in position, a relatively long gear on the second shaft, an idler gear between said spur gear and said relatively long gear, a collar movable along and turnable about said shaft, a radially extending arm fixed to said collar, a rod fixed to said arm in spaced relation to the second shaft and extending in parallel relation to said relatively long gear, a bracket on the inner end of said rod, a movable idler gear supported by said bracket on an axis parallel with that of said long gear, a stepped gear secured to said feed screw in spaced relation to the relatively long gear but parallel therewith, and said collar adjustable about and along said second shaft to shift said arm, rod and bracket along said relatively long gear and about the same on the axis thereof to mesh the movable idler gear with the relatively long gear and a chosen step of said stepped gear to thereby drive the feed screw at a chosen predetermined speed, and means to secure said collar in position on said second shaft.

40 4. The mechanism as in claim 3 including a housing enclosing said gearing, a stepped bracket at the outer side of said housing, a finger piece fixed to said radially extending arm, and said finger piece located to engage steps of said bracket corresponding with the steps of said gear to visually indicate the location of said movable idler gear within said housing.

45 5. The mechanism as in claim 3 including a housing enclosing said gearing, a stepped bracket at the outer side of said housing, a finger piece fixed to said radially extending arm, and said finger piece located to engage steps of said bracket corresponding with the steps of said gear to visually indicate the location of said movable idler gear within said housing.

5. In an apparatus for recording sound on a disc, a turntable, a carrier, a recording head on said carrier, a feed screw on said carrier and operable to feed said head across a record blank on said turntable, a gear drive from the top of said turntable to said feed screw and including a worm driven from said turntable, a shaft, a worm gear meshing with said worm and driving said shaft, a spur gear on said shaft, a second shaft spaced from the first shaft and parallel with the feed screw, a relatively long gear on the second shaft, an idler gear between said spur gear and said relatively long gear, a movable idler gear mounted on an axis parallel with that of said long gear, a stepped gear secured to said feed screw in spaced relation to the relatively long gear but parallel therewith, and means for shifting said movable idler gear along said relatively long gear and about the same on the axis thereof to mesh the movable idler gear with the relatively long gear and a chosen step of said stepped gear to thereby drive the feed screw at a chosen predetermined speed.

6. In an apparatus for recording sound on a disc, a turntable, a recording head, a swiveled removable carrier mounting said recording head and adapted to position the same over a record blank on said turntable, a feed screw mounted

5 by said carrier in operative relation to said recording head to feed the latter across a record blank on said turntable, means to drive said feed screw from the top of said turntable, and said last means including a shaft parallel with said feed screw, a stepped gear and another gear mounted one on said shaft and the other in driving relation with said feed screw, means to drive the gear on said shaft from the turntable, and a movable gear manually shiftable to gear said other gear with a chosen step of said stepped gear.

10 15 20 25 7. In an apparatus for recording sound on a disc, a turntable, a recording head, a swiveled removable carrier mounting said recording head and adapted to position the same over a record blank on said turntable, a feed screw mounted by said carrier in operative relation to said recording head to feed the latter across a record blank on said turntable, means to drive said feed screw from the top of said turntable, and said last means including a stepped gear concentric with and in driving relation to said feed screw, a gear driven from the top of said turntable, and means to drive said stepped gear through a chosen step thereof from said gear driven from the top of said turntable.

HERBERT S. BERLINER.
